US00D392627S

United States Patent [19]

Kondo

[11] Patent Number: Des. 392,627

[45] Date of Patent: **Mar. 24, 1998

[54] **UNIT FOR EXTENSION OF FUNCTION OF ELECTRONIC COMPUTERS**

[75] Inventor: **Osamu Kondo**, Tokyo, Japan

[73] Assignee: **Kabushiki Kaishi Toshiba**, Kawasaki, Japan

[**] Term: **14 Years**

[21] Appl. No.: **68,102**

[22] Filed: **Feb. 6, 1997**

[30] **Foreign Application Priority Data**

Aug. 6, 1996 [JP] Japan 8-23476

[51] LOC (6) Cl. **14-02**

[52] U.S. Cl. **D14/107**

[57] **CLAIM**

The ornamental design for a unit for extension of function of electronic computers, as shown and described.

DESCRIPTION

FIG. 1 is a top, front and right side perspective view of a unit for extension of function of electronic computers showing my new design;

FIG. 2 is a front elevational view thereof;

FIG. 3 is a top plan view thereof;

FIG. 4 is a bottom plan view thereof;

FIG. 5 is a rear elevational view thereof;

FIG. 6 is a right side elevational view thereof;

FIG. 7 is a left side elevational view thereof; and,

FIG. 8 is a reference perspective view thereof showing the unit in a used position with a laptop computer being shown in broken lines for illustrative purposes only and forming no part of the claimed design.
